UNITED STATES PATENT OFFICE.

MATTHIAS SCHWEMBERGER, OF CINCINNATI, OHIO.

BUNG.

SPECIFICATION forming part of Letters Patent No. 356,379, dated January 18, 1887.

Application filed December 11, 1886. Serial No. 221,318. (Model.)

To all whom it may concern:

Be it known that I, MATTHIAS SCHWEMBERGER, of Cincinnati, Hamilton county, Ohio, have invented a new and useful Improvement 5 in Bungs, of which the following is a specification.

My said improved bung is of composite material—to wit, malleable iron, india-rubber, and animal membrane, and is designed to be 10 used with the conical metallic bushings which now customarily line the bung-holes of beer-kegs.

In the accompanying drawings, Figure 1 is an elevation of my bung in position within a 15 metal bushing, shown in section. Figs. 2 and 3 are sections of said bung on the lines 2 2 and 3 3, respectively. Fig. 4 is an under side view of the nipple with its attached valve.

The bung-body 1, which is preferably of malleable cast-iron, has an expanded top or head, 2, to receive the blows of the driving-mallet and to facilitate subsequent extraction of the bung by a claw-bar or other suitable instrument introduced around the neck 3. Below 25 the said neck 3 an expanded portion or collar, 4, has a circumferential groove, 5, for an india-rubber band, 6, which, when the bung is

driven firmly home within the bushing, as shown in Fig. 4, binds tightly within the bushing and hermetically closes the keg. 30

7 is a downwardly-extending nipple, which is screw-threaded exteriorly to receive a protecting-cap, 8, having a ventage, 9.

A T-formed central passage, 10, is guarded at its lower extremity by an inwardly-opening 35 valve, 11, preferably composed of some animal membrane—such as gut or bladder. The valve 11 permits air to enter the keg whenever the interior pressure falls below that of the external atmosphere, but prevents any escape of the 40 imprisoned gases.

I claim as a new article of manufacture—

The composite bung, consisting of the described combination of the metallic body 1, having the circumferential groove 5, containing the rubber band 6, and having the inwardly-opening valve 11 upon the nipple 7 protected by the cap 8, as set forth. 45

In testimony of which invention I hereunto set my hand.

MATTHIAS SCHWEMBERGER.
